Attorney.

UNITED STATES PATENT OFFICE.

CHARLES H. HERMAN AND FRANK G. SCHROER, OF KANSAS CITY, MISSOURI; SAID
FRANK G. SCHROER ASSIGNOR TO SAID CHARLES H. HERMAN.

WELL-DRILLING APPARATUS.

Application filed January 7, 1924. Serial No. 684,770.

To all whom it may concern:

Be it known that we, CHARLES H. HERMAN and FRANK G. SCHROER, citizens of the United States, residing at Kansas City, in the county of Jackson and State of Missouri, have invented certain new and useful Improvements in Well-Drilling Apparatus, of which the following is a specification.

Our invention relates to apparatus for 10 drilling wells and while it may be employed to advantage in drilling different kinds of wells it is especially efficient in drilling deep wells, such as oil or artesian wells.

Important features reside in a hammer for 15 striking blows to force the drill bit through hard pan and rock encountered when drilling the well, and in hydraulic mechanism for lifting said hammer preparatory to its delivering each blow, said mechanism being 20 actuated at little additional cost by the same water which is forced into the well to flush out the sediment caused by drilling with a rotary drill.

Other features will hereinafter appear, 25 and in order that the invention may be fully understood, reference will now be had to the accompanying drawing, in which:

Fig. 1 is a vertical section partly in elevation showing the mechanism constituting 30 the present invention.

Fig. 2 is an enlarged broken section on line II—II of Fig. 1.

Fig. 3 is a cross section on line III—III of Fig. 2.

Fig. 4 is an enlarged broken section on line IV—IV of Fig. 1.

Fig. 5 is a cross section on line V—V of Fig. 4.

Referring now to the different parts, 2 40 designates a tube closed at its upper end by a plug 4 connected to pipes 6 and 6^a, the former of which extends above the top of the well. The pipe 6^a extends upwardly into the pipe 6 to form a trap 6^b for catching coarse sediment carried in by the water which is forced to the bottom of the well to flush out the borings.

8 designates a cylinder secured within the tube 2 and connected at its upper end to a 50 pipe 10 secured at its upper end to the plug 4 and communicating with the pipe 6^a.

12 designates a hollow piston reciprocably arranged within the cylinder 8 and having its interior divided into two chambers 14 55 and 16 by an oblique partition 18. The pis-

ton chamber 14 has upper and lower ports 20 and 22, respectively, controlled by a valve 24 which is caused to alternately shift its position to open and close the ports 20 and 22, by coil springs 26 and 28 which successively contact the cylinder heads 30 and 32, respectively. The piston chamber 16 has upper and lower ports 34 and 36, respectively, controlled by a valve 38, which, like the valve 24, is caused to shift its position 60 by springs 40 and 42 that successively contact the cylinder heads 30 and 32, respectively.

The piston 12 is provided at its upper side with a tubular stem 44 which communicates with the piston chamber 14 and extends upwardly into the pipe 10 through a stuffing box 46 carried by the cylinder head 30. The piston 12 is provided at its lower side with a tubular stem 48 which 70 communicates with the piston chamber 16 and extends therein through a stuffing box 50 on the lower cylinder head 32.

The lower end of the piston stem 48 terminates in the bore 52 of a head 54 provided 80 at its upper portion with a stuffing box 56 through which said stem 48 extends. The head 54 has a reduced portion 58 of angular cross section loosely embraced by a nut 60 threaded into the lower end of the tube 2 and 85 cored out to loosely fit the angular portion 58 of said head 54 for the purpose of rotating the same and a drill bit 62, as will hereinafter appear. For convenience in placing the nut 60 around the reduced portion 58 of 90 the head 54, said nut is made in two parts 61, as shown more clearly by Fig. 5. The reduced portion 58 is longer than the nut 60, so that the head 54 may move up and down to a limited extent independently of 95 said nut 60, for a purpose which will hereinafter appear.

The bit 62 has ducts 64 extending from end to end and communicating with the bore 52 of the head 54. Packing 65 is interposed 100 between the head 54 and the nut 60 to prevent water and débris from entering the lower end of the tube 2.

66 designates a hammer reciprocably arranged within the tube 2 and provided with 105 a central bore 68 through which the piston stem 48 freely extends. The upper end of the hammer 66 has a cavity 67 and an internal flange 70 with a beveled upper surface 71 for engagement by a pair of hooks 72 110

mounted intermediate their ends on pivots 74 carried by arms 76 projecting from a collar 78 secured to the piston stem 48 by suitable means such as a set screw 80. The lower 5 ends of the hooks 72 are normally forced apart to engage the internal flange 70 of the hammer 66 by springs 82 secured to said hooks 72 and bearing against the intervening piston stem 48. The lower ends of the 10 hooks 72 are beveled as indicated at 84, so that when they descend and contact the beveled upper surface 71 of the flange 70 they will be guided inwardly thereby until they pass beneath said flange 70, whereupon 15 they will be forced under the same by the springs 82.

In practice the bit 62 and the tube 2 with the mechanism assembled in the latter is lowered and rotated by the pipe 6. As the 20 drilling operation proceeds, the weight of the apparatus resting on the lower shoulder 86 of the head 54 aids the bit 62 in its boring operation. The bit 62 supports the head 54 with its shoulder 88 spaced above 25 the nut 60, so that the impact of the hammer 66 against said head 54 will be transmitted to said bit 62 instead of to the remainder of the apparatus. Assuming that the hammer 66 is resting upon the head 54, 30 the operation is as follows: Water forced through the pipe 6 from the top of the well to clear the bottom of the latter of débris caused by the boring operation, flows through the pipe 6^a, the upper piston 35 stem 44, the piston chamber 14 and into the upper portion of the cylinder 8 through the port 20. The pressure of the water upon the piston 12 forces the same downwardly, during which operation the water 40 below said piston 12 escapes from the cylinder 8 through the port 36, the piston chamber 16, the lower piston stem 48, the bore 52 in the head 54, and the ducts 64 in the bit 62. The downward stroke of the piston 45 12 carries the hooks 72 below the flange 70 and causes the springs 28 and 42 to contact the cylinder head 32 and be compressed sufficiently to shift the valves 24 and 38 upwardly until they close the ports 20 and 50 36, said valves 24 and 38 being held in raised position by the pressure of the water in the chambers 14 and 16, respectively. The water then passes through the piston 55 chamber 14 and the port 22 and forces the piston 12 on its upward stroke, the water escaping from the upper portion of the cylinder 8 to the piston stem 48 through the port 34 and the piston chamber 16. As the piston 12 travels upwardly it carries 60 the hooks 72, which, having engaged the under side of the flange 70, lift the hammer 66 until the upper ends of said hooks 72 are spread apart by the conical end 90 of the stuffing box 50, whereupon said hooks 65 72 release the hammer 66 which descends

by the force of gravity and delivers a blow upon the head 54, the resultant impact aiding the bit 62 in its boring operation. The piston 12 continues on its downward stroke until the springs 26 and 40 are compressed against the cylinder head 30, whereupon they restore the valves 24 and 38, respectively, to their initial position so that the water may again flow through the port 20 and force the piston 12 on another 70 downward stroke. The foregoing operations are repeated as long as desired.

At times it is desirable to stop the operation of the hammer 66 and yet permit the water to flow to the bottom of the well to 80 clear the débris therefrom. This is accomplished by raising the tube 2 until the nut 60 engages the shoulder 88. Raising of the tube 2 also lifts the cylinder 8 and the hooks 72, so that when the same are carried downward by the piston 12 they will not descend far enough to engage and lift the hammer 66, which is permitted to remain idle on the head 54 until the tube 2 is again lowered to carry the nut 60 down 85 upon the shoulder 86, which is supported by the bit 62 resting on the bottom of the well.

The tube 2 not only holds the different parts in proper relation to each other, but 90 prevents débris from lodging on said parts and interfering with their proper operation, especially the hooks 72, the hammer 66 and the head 54.

As shown by Fig. 4 the drill bit 62 is removable from the head 54, it being screwed therein so that different bits may be used as required, according to the formation of the rock or soil through which the well is 100 being drilled.

From the foregoing description it is apparent that we have provided an apparatus embodying the advantages above pointed out, and while we have shown and described the preferred construction, combination and arrangement of parts we reserve the right to make such changes as properly fall within the spirit and scope of the invention as claimed.

Having thus described our invention, 115 which we claim and desire to secure by Letters Patent, is:

1. In a drilling apparatus a hammer, means for engaging said hammer to raise the same, a hollow reciprocating piston for actuating said means, a partition dividing the interior of said piston into chambers having ports, valves for controlling said ports, a cylinder in which the piston operates and cooperates therewith in shifting said valves to effect alternate closing of the ports, means for effecting the release of the hammer so that the same may deliver a blow to force the drill bit downwardly, and a tubular piston stem communicating 120

with one of the piston chambers and extending through one end of the cylinder and a bore in the hammer.

2. In a drilling apparatus a head carrying a drill bit, a hammer associated with said head and provided with a flange, spring-pressed means for engaging said flange and raising said hammer, hydraulic mechanism for raising and lowering said

spring-pressed means, and an element for 10 disengaging said spring-pressed means from the hammer so that the same may deliver a blow to the head.

In testimony whereof we affix our signatures.

CHARLES H. HERMAN.
FRANK G. SCHROER.
